CARTON FOR STORING AND SHIPPING OR THE LIKE

Herbert S. Collin, Newton, Mass.

Application May 19, 1959, Serial No. 55,974

Term of patent 14 years

(Cl. D58—12.6)

Fig. 1.

Fig. 2.

Fig. 3.

Fig. 1 is a top plan view of a carton for storing and shipping or the like, embodying my design;

Fig. 2 is a front elevation of the carton; and

Fig. 3 is a perspective view of the carton.

The front sides and back of the carton are alike and the bottom is plain.

The drawing is lined for contrasting colored areas. The design for the carton disclosed is characterized by the solid black lines comprising the groups of small

lines on the sides and top of nonuniform length, the heavy circumferential lines on top and the heavy semi-circular lines and triangles on the sides as shown.

I claim:

The ornamental design for a carton for storing and shipping or the like, substantially as shown and described.

No references cited.
